PROCESS OF AERATING WATER IN MAKING ICE.

REISSUED

1,161,219.

Specification of Letters Patent. Patented Nov. 23, 1915.

Continuation in part of applications Serial No. 6,987, filed February 9, 1915, and Serial No. 17,617, filed March 29, 1915. This application filed July 21, 1915. Serial No. 41,026.

To all whom it may concern:

Be it known that I, WILLIS B. KIRKPATRICK, a citizen of the United States of America, residing in the city of Baltimore, 5 State of Maryland, have invented certain new and useful Improvements in Processes of Aerating Water in Making Ice, of which the following is a specification.

This application is a continuation in part 10 of each of my two co-pending applications, Serial Nos. 6,987 and 17,617.

The principal difficulty encountered in the practice of the aeration method in the past is that incident to maintaining an uninterrupted flow of air until the formation of the 15 cake of ice has been substantially completed. The two principal sources of interruption which are of importance in this connection are due to the formation of frost first in the 20 drop pipe which leads air downward to the point where it is discharged at the bottom of the can, and second, the formation of frost in the cooling pipes. Also, the formation 25 of ice in the can sometimes closes the mouth of the tube and the air system is sometimes blocked by the deposit of rust, sediment and the like. These latter difficulties are more fully treated in the parent application.

30 The different methods of aerating water in use are classified as high and low pressure. In the practice of the high pressure process, the air is first compressed to a comparatively high degree as fifty or sixty pounds per 35 square inch and then cooled to near the freezing point to dehydrate it, when it is again permitted to expand to about eighteen to twenty-five pounds, the high pressure being used to get excessive dehydration. From 40 this point the air pressure is again reduced by throttling and the air is led through a pipe in the corner of the freezing can, or otherwise in contact with or in close proximity to the brine, to the bottom of the freezing 45 can near the center where the air is released. This apparatus is subject to frequent stoppage owing to the formation of frost in the drop pipe and in the air cooling coils as just described. Also the compression of the air 50 to fifty or sixty pounds which is incident to this process is expensive.

The principal objection to the low pressure method in which the pressure is only

sufficient to keep the water in agitation and which is therefore less expensive is that the 55 passage of the air upward through the can is, in the natural course of things, certain to become blocked by the formation of ice. In the applicant's invention under discussion, the passage of the air upward through the 60 can is kept open by the air pressure which, though normally low, builds up automatically when the outlet is obstructed.

The present invention relates to a method by means of which the high and low pressure 65 systems are so combined as to obtain the advantages and overcome the permanent defects incident to each. To this end I have evolved a new method of operation which is such that the closure of the cooling pipes by 70 means of frost is wholly impossible, and in connection with this cooling system, I so deliver the air at the bottom of the cans that it is not cooled below the freezing point until the formation of the cake of ice is practically 75 complete. This greatly reduces the formation of frost in the drop pipe and renders the excessive dehydration practised in the high pressure system wholly unnecessary, for it will be understood that the high pressure 80 and low temperatures used are for the purpose of precipitating as much moisture as possible from the air and to thus overcome in a different way the tendency to choke the drop pipe with frost. In this connection it 85 will be noted that the high pressure system had always been used with the delivery pipe passing in close proximity to the brine, the temperature of which is usually about 14° F., while the delivery pipe in the present 90 instance is near the center of the body of water to be frozen so that it does not come in contact with temperatures sufficiently low to freeze the moisture in the air until the formation of the cake is complete, or nearly 95 complete. By combining this feature with the dehydration produced by cooling with clear water at low temperatures, obstruction by frost is avoided, both in the drop pipe and the cooling coils.

100 By thus avoiding the necessity for excessive dehydration and providing a cooling means which cannot clog, and by other features hereinafter referred to, I have reduced the expense incident to compressing the air 105 and increased the efficiency of the operation.

In the accompanying drawings, I have illustrated so much of my apparatus for aerating water in the manufacture of ice, as is necessary to complete understanding of 5 the invention.

Figure 1 is a vertical section of a portion of a brine tank showing a number of cans in section and the drop pipes and supply pipes in elevation; also the air cooling device in elevation; and Fig. 2 is a section on the line 2, 2 of Fig. 1, showing the cooler in cross section.

Referring to the drawings by numerals; the apparatus as shown includes a cooling 15 coil 1 having an inlet 2 to which air is supplied at a medium pressure, preferably from twelve to twenty-five pounds above atmosphere, and an outlet 3 to the header 4 of the system, by means of which the air 20 for aerating the water is delivered to the cans. The cooling apparatus also includes an ammonia coil 5, the helices of the ammonia coil being arranged in a vertical plane as are those of the air coil, the latter 25 being placed directly under the former, as shown in cross section in Fig. 2, so that all the pipes of each cooling unit are in a single vertical plane. The inlet 6 of the ammonia coil is at the bottom, and the outlet 7 at 30 the top.

Just over the ammonia coil, I provide a water delivery pipe 8 which is preferably slotted throughout its entire length as at 35 9 or otherwise provided with suitable orifices to discharge water and permit it to flow uniformly over the entire coil. Water is supplied to the delivery or sprinkler pipe 8 by a pump 10 or other suitable and convenient means, either taking the water from 40 the catch basin 11 beneath the coils or from an outside source by way of the pipe 12.

An important feature of the cooling system resides in the use of pure water instead of brine or the equivalent as a cooling 45 medium in connection with the ammonia and air coils, and of valves, either automatically or manually operated at 13 and 14 by means of which the pressure and expansion of the ammonia vapor may be so regulated 50 as to give the desired temperature, but even in the absence of such regulation of the pressure of the ammonia vapor, the air pipes cannot be cooled below freezing because the cooling effect is transferred from 55 the ammonia pipes to the air pipes by means of fresh water, flowing in a film by gravity from the ammonia to the air pipes, and this flow could not of course be maintained at freezing temperatures. Substantially pure 60 water having the same freezing point as pure water may be used with the same result. Under these circumstances it is practically impossible to reduce the temperature of the air to a point lower than five 65 or six degrees Fahrenheit above the freez-

ing point and at this temperature, the tubes cannot become stopped with frost. The temperature of the air in the dehydrator may go much higher without detriment to the operation of the plant.

An important feature of my method consists in the handling and delivery of the air for agitating the water at temperatures well above freezing. The most convenient way of doing this is by using clear water as a 70 heat transfer medium in the dehydrator but other means for cooling the water and dehydrating it may be employed within the scope of my invention. The use of clear water for this purpose is one feature only 75 of several involved in the method which is the subject of the invention. As I have stated, the air passes through the cooling coil at a medium pressure which may be varied from twelve to twenty-five pounds 80 above the atmosphere, but at this pressure with average humidity, a considerable amount of condensation takes place and the moisture thus condensed may be removed by a suitable trap or drip of commercial 85 variety, shown at 15.

In Fig. 1, at the left, I have shown a portion of a brine tank 16 of the type commonly used in the manufacture of can ice, together with a number of cans 17 in operative position for freezing. The area occupied by the tank is traversed by headers 4 leading from the cooler. From the header 4 a lateral extends outward between each two lines of cans and inserted in each lateral 100 between each pair of cans is a four-way fitting, or cross 19 which may contain a reducing valve or orifice by which the normal air pressure is dropped to a point slightly above atmosphere, as shown and described 105 in my co-pending application referred to. Two arms of each cross-fitting 19 preferably extend along the sides of the adjacent cans to a point near the center and the air is led by suitable means as the connection 22, 110 shown in Fig. 1, to the drop pipe 21 which discharges the air at the bottom near the center of the can. The drop pipe which I use is straight so that it may be conveniently withdrawn from the cake, after heating slightly to release it, and it is set into the can either vertically in the center, as in the current application, or in an inclined position as described in my co-pending application Ser. No. 17617. The inclined pipe 115 21, as shown, is supported by the bracket 23, fully described in the last named application, and is connected to the air distributing system by a flexible hose 22, the rigid portion of the pipe 21 being straight and conveniently arranged for the introduction of a steam nozzle by means of which it may be released, and then being perfectly straight may be conveniently withdrawn.

While the pipe as shown does not occupy 120

the axial center of the can, it delivers at the bottom near the center and as freezing takes place from the sides and bottom, the last part frozen being the central portion, 5 near the top, the pipe is in this way protected from the low temperature of the brine. In fact, it does not become frozen until the freezing of the cake of ice is well advanced and even then, being adjacent the 10 free water it is not subject to a temperature appreciably below the freezing point, so that obstruction of the drop pipe by frost when delivering air, cooled as described herein by the flow of clear water over the 15 air cooling coil, is not an element which need be taken into account in the conduct of the plant. The advantages of the inclined pipe arranged as described, are fully set forth in my co-pending application No. 20 17,617, and need not be enlarged upon in this specification.

While the preferred method of protecting the air pipe from the low temperature of the brine is by passing the drop pipe through 25 the body of water to be frozen keeping it well away from the sides of the can, the pipe may be otherwise protected from the low temperature of the brine, thus accomplishing the method of my invention, by other 30 means obvious to those skilled in the art, though these devices are considered less practical than that specifically described.

The operation of the system will be described in connection with the process of 35 my invention. Starting with the cans filled with water and the drop pipes in position as shown in Fig. 1, the connections being made from each cross-fitting 19 to the corresponding drop pipes 21 by means of a hose 40 or flexible tube 22, ammonia is applied to the coil 5 by way of the inlet 6. Air at medium pressure, determined as sufficient to keep the air passage to the can open until freezing is complete, is applied to the coil 1 by way of 45 the inlet 2 and fresh water is passed over the ammonia and air coils as indicated. The temperature of the air pipes is controlled and kept above freezing by using clear water as a heat transfer means, fresh water 50 serving to prevent the reduction of the temperature of the air to an extent sufficient to cause frost in the pipes. The water which may be condensed by this drop in pressure, the quantity depending upon the humidity 55 of the air, there being none under some conditions, is removed from the drip 15 and the cooled air is delivered to the header 4 whence it is distributed by way of crosses 19 and the drop pipes 21. It will be understood 60 that the initial pressure at the inlet 2 is substantially maintained throughout the system as far as the reducing orifices referred to herein and described in the current application. At this point the air is expanded 65 and throttled down to a pressure slightly

above atmosphere, for a higher pressure would interfere with freezing and would blow the water from the cans.

To keep the passage 4 of the drop pipe from being closed by the ice formed in the can in the regular process of freezing, the full initial pressure is sometimes necessary. This is obtained by the simple expedient of permitting the air which escapes to back up until it reaches the pressure of the coil or 75 inlet or becomes sufficient to open the passage through the ice.

In practice it is found that with twelve or fifteen pounds pressure at the air inlet, the drop pipe, constructed as described, will 80 keep open until the ice cake is complete. If any obstruction takes place, this is quickly broken by the rise of pressure.

It will also be apparent that by the use of 85 a cooler for the compressed air, using clear water as a means for abstracting the heat from the air, which prevents the formation of frost in the cooling coil, combined with a drop pipe which is protected from the lower temperatures by being placed near the center of the can, I have rendered the use of high pressures to produce excessive dehydration unnecessary for formation of frost in the drop pipe is practically eliminated. This also results in greatly increased economy 90 and a system of unparalleled efficiency in that obstructions of the air pipe, resulting in white ice, are so infrequent that a practically uniform product of the highest quality is produced with the least expenditure for labor and attendance.

I have thus described the method which is the subject of my invention specifically and in detail in order that its nature and operation may be fully understood; however, the specific terms herein are used in their descriptive rather than in their limiting sense and the scope of the invention is defined in the claims.

I claim:

1. A process of agitating water by air in making ice which consists in compressing the air to a pressure in the vicinity of from twelve to twenty-five pounds above atmosphere, dehydrating the air by cooling it, reducing the pressure, passing such air through the mass of water to be frozen following a path near the center, and delivering air into the mass of water at the bottom.

2. A process of agitating water by air in making ice which consists in compressing the air to a pressure of from twelve to twenty-five pounds above atmosphere, dehydrating the air by cooling it to a temperature well above freezing, reducing the pressure to a point slightly in excess of that of the atmosphere, passing such air through or near the center of the water to be frozen, and delivering it to the water near the bottom of the mass.

3. A process of agitating water by air in the manufacture of ice which consists in compressing the air to a pressure of from twelve to twenty-five pounds above atmosphere, dehydrating the air by cooling it using substantially clear water as a heat transfer medium, reducing the pressure and passing the air through or near the center of the mass of water to be frozen, and delivering the air near the bottom of the mass of water.

4. A process of agitating water by air in making ice which consists in compressing the air, dehydrating the air by cooling it using substantially clear water as a heat transfer medium, reducing the pressure, passing such air through or near the center of the mass of water to be frozen and delivering such air into the bottom of such mass of water.

5. A process of agitating water by air in making ice which consists of compressing the air to a pressure in the vicinity of from twelve to twenty-five pounds above atmosphere, cooling the air to dehydrate it, the temperature being maintained at least five or six degrees above freezing, reducing the pressure so that it is slightly in excess of that of the atmosphere, passing such air through or near the center of the mass of water to be frozen and delivering it near the bottom of the mass of water.

6. A process of removing moisture from compressed air in the manufacture of ice which consists in circulating practically pure water in indirect heat exchange with a refrigerant, bringing such water into indirect heat exchanging relation with the compressed air whereby a portion of the mois-

ture in said air is condensed, and then separating such condensed moisture from the air.

7. A process of agitating water by air in making ice which consists in compressing the air, dehydrating the air by cooling it to a temperature at least five or six degrees above freezing, reducing the pressure of the air and passing the air through or near the center of the mass of water to be frozen, and delivering the air to the mass of water near the bottom.

8. A process of removing moisture from compressed air which consists in circulating practically pure water in indirect exchange with a refrigerant, bringing such water into indirect heat exchanging relation with the compressed air whereby a portion of the moisture in said air is condensed, and then separating such condensed moisture from the air.

9. A process of manufacturing ice which consists in freezing the water in cans in a non-freezing liquid, as brine, at a temperature well below the freezing point of water, agitating the water by air by compressing the air, and dehydrating the air by cooling it to a temperature at least five or six degrees above freezing, leading it to and introducing it into the mass of the water, near the bottom, the air being protected in its passage from the temperature of the brine.

Signed by me at Baltimore, Maryland this 20th day of July 17th, 1915.

WILLIS B. KIRKPATRICK.
